ARTICULATED TRACTOR

Henry Dreyfuss and James M. Conner, South Pasadena, Calif., and Harold G. Borsheim, Lyle E. Miller and Leland G. Gilbert, Dubuque, Iowa, assignors to Deere & Company, Moline, Ill., a corporation of Delaware

Filed Aug. 12, 1968, Ser. No. 13,084

Term of patent 14 years

Int. Cl. D12—09

U.S. Cl. D14—3

FIG. 2

FIG. 3

FIG. 4

FIG. 1 is a left side perspective view of an articulated tractor showing our new design.

FIG. 2 is a right rear perspective view of the tractor.
FIG. 3 is an upper front perspective view of the tractor.
FIG. 4 is an upper rear perspective view of the tractor.
The dominant features of our design reside in the portion of the drawings shown in full lines.

We claim:

The ornamental design for an articulated tractor, substantially as shown and described.
